(57) **CLAIM**

The ornamental design for an intake manifold set, as shown and described.

DESCRIPTION

FIG. 1 is a front perspective view of an intake manifold set showing my new design shown mounted on top of an engine;

FIG. 2 is an enlarged front perspective view thereof;

FIG. 3 is an enlarged rear perspective view thereof;

FIG. 4 is an enlarged top view thereof; and,

FIG. 5 is an enlarged bottom view thereof.

The broken lines shown in FIG. 1 are for illustrative purposes only and form no part of the claimed design.
